UNITED STATES PATENT OFFICE.

ALBERT A. BRUDER, OF DETROIT, MICHIGAN.

BASE-BALL-GAME APPARATUS.

1,287,208.

Specification of Letters Patent. Patented Dec. 10, 1918.

Application filed April 20, 1918. Serial No. 229,667.

To all whom it may concern:

Be it known that I, ALBERT A. BRUDER, a citizen of the United States of America, residing at Detroit, in the county of Wayne and State of Michigan, have invented certain new and useful Improvements in Base-Ball-Game Apparatus, of which the following is a specification, reference being had therein to the accompanying drawings.

10 This invention relates to a baseball game, and my invention aims to provide a game apparatus which will require considerable skill to successfully play, and at the same time afford considerable amusement to juvenile niles or persons interested in baseball.

15 The game apparatus includes a novel board and novel means for projecting a ball in different directions over the board. According to a set of rules the game, when played, resembles somewhat an ordinary baseball game and may be participated in by any number of players, who may choose teams or sides and conduct the miniature game somewhat similar to the outdoor baseball game.

20 25 My invention will be hereinafter specifically described and then claimed, and reference will now be had to the drawing wherein—

30 Figure 1 is a plan of the game apparatus; Fig. 2 is an enlarged longitudinal sectional view of the same, partly broken away, and

Fig. 3 is a perspective view of a modified form of ball projecting device.

35 The game apparatus comprises a comparatively flat hollow box 1 having the top thereof constituting a base ball game on which is printed or otherwise marked the outline of a baseball diamond or square 3.

40 The top of the box or field 2 has a plurality of depressions or pockets, some or all of which may have the marginal edges thereof provided with upstanding ribs 4, so that a ball cannot accidentally roll into the pockets.

45 Those pockets designated 5, 6 and 7 represent the first, second and third bases of the diamond and adjacent the pockets are semi-circular pockets 8, 9 and 10 representing the position of basemen at the pockets 5, 6 and 7.

50 The top of the box or field 2 has a pitcher's pocket 11, outfields' pockets 12, bunt ball pockets 13, foul pockets 14, and a catcher's pocket 15.

55 At the batter's position on the field 2 is a socket 16 to receive the reduced end 17 of a

swiveled upright 18. Pivoted in the upper end of the upright 18 and frictionally held thereby is a tiltable ball supporting member 19 having a groove 20 to receive a ball 21. 60 Adjacent the forward end of the groove 20 is a ledge or bumper 22, which when encountered by the ball 21, causes said ball to assume an upright flight, similar to a fly ball.

65 The upright 18 is provided with a bracket 23 and pivotally connected to said bracket is a spring pressed hammer 24 that serves as a bat. The upper end of the hammer 24 may be pulled rear-wardly and when released is adapted to impinge against the ball 21 and the rear end of the ball support 19, causing the ball 21 to be projected outwardly over the field or top of the box 1.

70 The upright 18 may be turned in its socket to point the ball support 19 in a desired direction, and said ball support may be adjusted and placed at a desired inclination relative to the field. In this manner the ball 21, having the ball 21, land at a desired place on the field 2.

75 In Fig. 3 of the drawing, there is illustrated a modified form of batting device, comprising a pocket 24 having a rock shaft 25 transversely of the top of said pocket. On the rock shaft 25 is a scoop 26 having a handle 27, said handle being connected by a coiled retractile spring 28 to the field or top of the box. A ball 29 is adapted to be 80 placed in the pocket 24 and by shifting the scoop 26 to place the spring under tension, and then by releasing the handle 27, the scoop 26 will project the ball 29 from the pocket 24 somewhat as a fly ball.

85 As stated in the beginning, the game may be played by two or more persons divided into teams, and if an uneven number of persons participate in the game, then there will be individual scores. The game is to 100 be played in innings and scored in innings, and if only two players participate then each is considered three times out to an inning. If three or five players participate, each player must play three times out to one 105 inning; five or six players in teams require six times out to one inning, and if nine players participate in teams it requires that nine players count to one inning.

110 To start the game with the ball striking device, as shown in Figs. 1 and 2, the device is first swung or aimed in the direction the

player desires the ball to travel, and then the hammer 24 retracted so that when it is released it will impinge against the ball 21 and discharge said ball over the field.

5 Various rules may be made as to the playing of the game, and as an instance of such rules, the following may be used.

The object of each player is to place a ball in the pockets 5, 6 and 7 and thus make 10 a home run. If a ball goes into either of the pockets 8, 9, 10, 11 and 12, the player may be considered out, or those balls which enter the pockets 8, 9 and 10 may be considered strikes, it being necessary for the 15 player to place the ball in the first base pocket before starting for the second base pocket 6.

Balls that enter the pockets 13 may be considered bunts and count as strikes.

20 Every ball that drops outside of a pocket may be called a ball and after every two balls the player may have an extra chance.

If a ball drops into a pocket and bounces out of it into another pocket, it will score 25 for what it may be when the ball stops.

Any ball that enters the pockets 14 may be considered a foul ball, and any ball entering the pocket 15 may be considered as being caught by the catcher and scoring as 30 a foul out.

With the scooping device shown in Fig. 3, the game is rendered more difficult as it is not always possible to determine the direction of the ball 29, and as before stated the

players may make such rules as to provide 35 an interesting game.

The infield of the game board may be countersunk relative to the outfield and the entire game apparatus may be finished to portray players and baseball paraphernalia. 40

What I claim is:—

1. In a baseball game apparatus, the combination with a box having the top thereof constituting a baseball field and the top of said box having pockets of various depths 45 therein, of a ball projecting device carried by the top of said box, and comprising an upright, a ball supporting member on said upright provided with a bumper, and means adapted for striking a ball on said supporting member.

2. A ball striking device for a game apparatus, comprising a swiveled upright, a tiltable ball supporting member on said upright provided adjacent its outer end with a bumper, and a spring pressed hammer carried by said upright and adapted to be retracted and released to impinge against a ball on said supporting member and cause said ball to strike the bumper of said supporting 60 member and bound therefrom.

In testimony whereof I affix my signature in the presence of two witnesses.

ALBERT A. BRUDER.
